CLAIM

The ornamental design for a personal cooling apparatus, as shown and described.

DESCRIPTION

FIG. 1 is a top, front, left isometric view showing my new design for a personal cooling apparatus wherein the bottom-operated handle is shown in a retracted position;

FIG. 2 is a bottom, front, left isometric view of FIG. 1;

FIG. 3 is a front elevational view of FIG. 1;

FIG. 4 is a rear elevational view of FIG. 1;

FIG. 5 is a left elevational view of FIG. 1;

FIG. 6 is a right elevational view of FIG. 1;

FIG. 7 is a top plan view of FIG. 1;

FIG. 8 is a bottom plan view of FIG. 1;

FIG. 9 is a top, front, left isometric view showing the design with its handle in an extended position;

FIG. 10 is a bottom, front, left isometric view of FIG. 9; and,

FIG. 11 is a right elevational view of FIG. 9.

(Continued)

The broken lines are included for the purpose of illustrating the portions of the personal cooling apparatus that form no part of the claimed design.
